UNITED STATES PATENT OFFICE.

ALVA D. JONES, OF PHILADELPHIA, PENNSYLVANIA.

TELEPHONE-TRANSMITTER.

1,118,780.

Specification of Letters Patent.

Patented Nov. 24, 1914.

Application filed May 7, 1914. Serial No. 837,031.

To all whom it may concern:

Be it known that I, ALVA D. JONES, a citizen of the United States, residing in Philadelphia, Pennsylvania, have invented certain Improvements in Telephone-Transmitters, of which the following is a specification.

One object of my invention is to provide a telephone transmitter which while being primarily designed to give the most perfect results as a sound receiving and transmitting instrument, shall at the same time be of the utmost simplicity of construction, its parts being few in number, substantial, durable and comparatively inexpensive. I also desire to provide a transmitter whose construction shall be such as to prevent "packing" of the carbon granules in its resistance cell and which shall transmit the sounds produced by the human voice without an accompanying blare or noise due to its bodily vibration or other causes.

A further object of the invention is to provide a transmitter which in addition to the above noted characteristics shall be so made that its parts may be assembled in a minimum of time, while the complete instrument shall be of such design as to practically eliminate the possibility of its getting out of order even after the lapse of long periods of time.

These objects and other advantageous ends I secure as hereinafter set forth, reference being had to the accompanying drawings, in which;

Figure 1 is a side elevation partly in section, illustrating the preferred form of my invention; Fig. 2 is a front elevation of part of a telephone transmitter, the face-plate and diaphragm being removed; Fig. 3 is a plan, partly in section, further illustrating the construction of the transmitter; Fig. 4 is a perspective of the resilient supporting member; Fig. 5 is a vertical section of a slightly modified form of the invention, and Fig. 6 is a section, on a greatly enlarged scale, illustrating a detail of my invention.

In the above drawings, 1 represents the upper part of the supporting standard of a telephone transmitter within which is pivotally mounted a hook 2 normally supporting the receiver 3.

On the upper part of the standard 1 is movably mounted a hollow metallic shell 4 having removably fixed to it a face-plate 5 carrying a mouth-piece 6 of the standard

construction, the shell being connected to the standard 1 by a horizontal pivot 7. Within the shell is mounted a body or solid mass 8 of resilient material such as rubber, either soft or partly or wholly vulcanized, the same being preferably of such form that its rear portion closely fits the rear part of the shell 4 and has an opening for the passage of the pivot pin 7. The front portion of the resilient body is substantially circular in elevation and the edge of its main portion is connected to a relatively thick ring 9 of substantially circular section through a comparatively thin neck portion 10, the construction being such that the plane of the front edge of the ring portion is spaced away from the plane of the relatively flat front face of the body. This latter is provided with a substantially cylindrical central recess 11 in which is mounted a resistance cell 12 of standard construction, there being a rearward extension or post 13 from said cell, cemented or otherwise fixed within a cavity in the body of the resilient mass 8. A rod or post 14 projecting from the front face of the resistance cell is connected to a diaphragm 15 of the customary form whose outer edges are clamped so as to form an airtight joint between the ring portion 9 of the resilient member 8 and the face-plate 5 which is customarily held to the shell 4 by screws 16, there being provided the customary gaskets 17 between the diaphragm, the member 8, and the face-plate.

As shown in Fig. 6, the outer or front end of the post 14 is threaded so that it may pass loosely through the center of the diaphragm 15 but an airtight joint or connection is made between these two parts by a body 20 of wax or other suitable sealing material, and thereafter the jam nuts 21 are placed on the post so that the inner one engages said sealing body.

While I preferably only partially vulcanize the neck and ring portions 10 and 9 of the resilient body 8, so that they are relatively springy while the base forming the remainder is relatively rigid, it is to be understood that said member may be wholly vulcanized or, in some instances, may be made of unvulcanized material, and while I preferably employ rubber, it is to be noted that other materials having more or less strongly marked resilient qualities may be substituted without departing from my invention.

The customary electrical connections are made to the terminals formed by the stem 13 and the rod 14 of the resistance cell and are led into the standard 1 through a passage 5 which is hermetically sealed in any suitable manner.

By practical experiment, I have found that an instrument constructed as above gives an unusually satisfactory and clear 10 transmission of sounds without any of the undesirable and annoying vibrations which are customarily present.

Not only is the instrument extremely simple in construction, but it may be assembled 15 with the utmost ease and speed and obviously the possibility of it becoming injured by long continued use, or even careless handling, is reduced to a minimum.

While, as above noted, I prefer to make the 20 entire mass of the member 8 of resilient material, with its neck and ring portions more resilient than the remainder, I may in some cases construct it as shown in Fig. 5, so that the part 18 which extends into the rear of 25 the shell 4 is in the form of a body of metal having a rectangular section, while the rubber or other resilient body 8^a is fitted or cast around this part to which it may be additionally attached in any desired manner.

30 It is to be noted that the diaphragm 15 makes airtight contact with the part 9 on which it is mounted and that the openings into the chamber containing the resistance 35 cell 12 are sealed so that the latter is effectively prevented from packing or other injury by dampness.

While I have illustrated and included in the claims an element described as a "resistance cell," it is to be understood that by 40 this term reference is had to that portion of the transmitter whose electrical functions or qualities are affected by the diaphragm in such manner as to cause variations of the current flow in the circuit of which it forms 45 a part.

It is to be understood that the relatively thin neck 10 by virtue of its proportions as well as because of its material, provides a yielding support for the peripheral part 9 50 and may in itself constitute the sole resilient supporting means for said part and the diaphragm 15, especially if the body 8 and the ring 9 are made of relatively unyielding material.

55 If found advisable to reinforce the rubber or other material forming the body 8 or 8^a, I may cast the latter around a perforated ring or plate 22 preferably flanged and made of spring metal extending through the neck 60 10 into the ring 9 and either engaging or approaching more or less closely the lug 18 in that form of the invention shown in Fig. 5.

I claim:

1. The combination in a telephone transmitter, of a supporting structure; a solid 65

mass of material mounted therein and having portions of varying degrees of resiliency; a diaphragm having its periphery in engagement with said mass of material; and a resistance cell operatively connected between the diaphragm and a portion of said mass of material whose resiliency is different from that engaged by the diaphragm. 70

2. The combination in a telephone transmitter, of a mass of material having relatively resilient and rigid portions; a casing inclosing the same; a diaphragm confined between a portion of the casing and the relatively resilient portion of said mass of material; and a resistance cell mounted between 80 the diaphragm and the relatively rigid portion of the mass. 85

3. The combination in a telephone transmitter of a body of resilient material having a central cavity; a resistance cell mounted in said cavity and rigidly connected to said body of material; with a diaphragm operatively connected to said cell and supported at its periphery on said body of resilient material. 90

4. The combination in a telephone transmitter of a casing; a mass of relatively resilient material including a peripheral portion connected to the body by a relatively thin yielding neck portion; a diaphragm clamped against said peripheral portion; and a resistance cell operatively connected to the diaphragm. 95

5. The combination in a telephone transmitter of a casing; a mass of rubber mounted therein and including a convex peripheral portion; a diaphragm clamped against said peripheral portion; with a resistance cell mounted within and directly connected to the body of said rubber mass and means 100 for operatively connecting said cell to the diaphragm. 105

6. The combination in a telephone transmitter, of a body of material having portions of different resiliency; a diaphragm 110 having its periphery in air-tight engagement with one portion of said body of material; with a resistance cell hermetically sealed within a cavity of said body, and connected between the diaphragm and a portion 115 of the body having a resiliency different from that of the part engaged by the diaphragm.

7. The combination in a telephone transmitter, of a supporting structure having an 120 integral yieldingly mounted peripheral portion; a diaphragm clamped against said portion; and a resistance cell operatively connected between the diaphragm and a relatively rigid portion of the supporting structure. 125

8. The combination in a telephone transmitter of a supporting structure; a body of resilient material mounted thereon and including a relatively thin neck portion and 130

a ring carried thereby; a reinforcing structure extending from the body through the neck into the ring portion; a diaphragm engaging said body; and a resistance cell 5 operatively connected to said diaphragm.

9. The combination in a telephone transmitter of a supporting structure; a body of rubber having relatively rigid and resilient portions of which the first is connected to 10 the supporting structure; a diaphragm mounted on the resilient portion; and a resistance cell mounted between the rigid portion and the diaphragm.

10. The combination in a telephone transmitter of a casing; a single structure therein having a relatively rigid portion connected to said casing and including a relatively resilient portion; a diaphragm; and a resistance cell connected between said diaphragm and the rigid portion.

11. The combination in a telephone transmitter of a casing having a hollow extension forming a hinge member for co-operation with a supporting standard; a structure 25 having a relatively rigid portion extending into the hollow of said extension and including an annular resilient portion; a diaphragm mounted on said latter portion; and a resistance cell in operative connection with 30 the diaphragm.

12. The combination in a telephone trans-

mitter, of a casing; a diaphragm; a resistance cell; and a structure having a rigid portion connected to the casing and supporting the resistance cell; said structure including an integral relatively resilient portion 35 supporting the diaphragm.

13. The combination in a telephone transmitter, of a casing; a body of rubber therein having rigid and resilient portions of which 40 the former is connected to the casing and the latter is annular in form; a diaphragm mounted on the resilient portion; and a resistance cell connected between the diaphragm and the rigid portion of said rubber 45 body.

14. The combination in a telephone transmitter of a body of resilient material having a central cavity; a resistance cell mounted in said cavity and rigidly connected directly 50 to said body of material at the bottom of the cavity; with a diaphragm operatively connected to said cell and supported at its periphery on said body of resilient material.

In testimony whereof, I have signed my 55 name to this specification, in the presence of two subscribing witnesses.

ALVA D. JONES.
